FIG. 1

FIG. 2

FIG. 3

FIG. 4

FIG. 1 is a perspective view from the bottom and one front corner of a wall-mounted light fixture incorporating my design;

FIG. 2 is a perspective view from the top and opposite front corner of such fixture;

FIG. 3 is a top plan view of said fixture; and

FIG. 4 is a bottom plan view of such fixture.

The diagonally shaded surfaces adjacent the ribbed front and on the top and bottom of the fixture are windows.

The wall is indicated in broken lines in FIGS. 3 and 4 for illustrative purposes only.

I claim:

The ornamental design for a wall-mounted light fixture, substantially as shown and described.
